E. LEVIN.

SKIRT MARKER.

APPLICATION FILED AUG. 19, 1916.

1,237,664.

Patented Aug. 21, 1917.

Inventor
Edward Levin.

By his Attorney
Maurice Block

UNITED STATES PATENT OFFICE.

EDWARD LEVIN, OF BROOKLYN, NEW YORK.

SKIRT-MARKER.

1,237,664.

Specification of Letters Patent. Patented Aug. 21, 1917.

Application filed August 19, 1916. Serial No. 115,798.

To all whom it may concern:

Be it known that I, EDWARD LEVIN, a subject of the Czar of Russia, residing at Brooklyn, Kings county, State of New York, have 5 invented certain new and useful Improvements in Skirt-Markers, of which the following is a full, clear, and exact description.

This invention relates to improvements in 10 skirt-marking devices or gages whereby a skirt can be marked circumferentially in order that it can be evenly cut off to the required length. My improved device is arranged in the form of a platform or stand- 15 ard slightly elevated from the ground and upon which a person can stand, the platform or support therefor carrying a movable arm to which is attached a vertical rod carrying 20 the gage. When a skirt is to be marked a woman will stand upon the platform and drape or place the skirt between the members of the marking gage, after which the skirt can be marked and cut.

My invention comprises certain novel features of improvement in this class of skirt-markers and in the combination and arrangement of parts which I will now proceed to describe in detail and finally point out in the appended claims, reference being 30 had to the accompanying drawing, forming part hereof, wherein—

Figure 1 is a top plan view of an embodiment of my invention;

Fig. 2 is a side view thereof, looking from 35 the right in Fig. 1;

Fig. 3 is an enlarged fragmentary sectional detail view of the marking gage element of the device;

Fig. 4 is an enlarged sectional plan view, 40 the section being taken on a line 4—4 in Fig. 3;

Fig. 5 is a fragmentary sectional view of a modified form of marking gage; and

Fig. 6 is a sectional plan view thereof, the 45 section being taken on a line 6—6 in Fig. 5.

As herein illustrated, my invention comprises a table 7 carried by a standard consisting of legs 8 and post 9, the post 9 pivotally supporting an arm 10 carrying a vertical post 11, in this instance a square post, to which is adjustably secured a marking-gage 12.

The gage 12 consists of a hub 13 having a square bore 14 to fit the post 11, a binding-screw 15 being employed to secure the gage in adjusted positions. The hub 13 supports

a curved marking-plate 16 by means of a bracket 17, and the post 11 pivotally supports a gage-arm 18 which is curved to match the curved plate 16. The gage-arm 60 18 is carried by a hub 19 rotatably mounted on the post 11. The hub 19 rests upon the hub 13 and is held in such engagement by a clamp 20 carried by the bracket 17. The clamp 20 carries an extension 21 which 65 overlaps the collar 22 on the hub 19. While the gage-arm 18 can be swung toward or away from the plate 16, it cannot be moved vertically upon the post 11. It will be seen that the gage-arm is provided with a relatively wide top portion, while the marking-plate 18 is comparatively thin but of considerable depth.

When a skirt is to be marked it is placed over the marking-plate 16 and between said 75 marking-plate and gage-arm 18, the gage-arm having been swung outwardly to permit the skirt to be placed between it and the marking-plate. After the skirt has been positioned the gage-arm will be swung 80 inwardly against the skirt to force the skirt firmly against the marking-plate. Before the skirt is marked, the gage will be adjusted vertically to the position where the skirt is to be marked. After having ad- 85 justed the gage, the arm 18 will be swung inwardly against the skirt, whereupon a marking element will be placed upon the top surface of the gage-arm 18 and moved along same in contact with the skirt. The broad 90 top surface of the gage-arm provides a table to support the marking element while it is being moved to mark the skirt. After the skirt has been marked to the extent of the gage, the arm 10 will be radially moved to 95 carry the gage to another position so that the mark already made upon the skirt can be continued or extended, and so on until the entire circumference of the skirt is marked. The gage-arm 18 is the only element of the 100 gage that is movable relative to the post 11. The marking plate 16 is fixed and moves only when the arm 10 is moved.

Fig. 5 illustrates another form of gage, consisting of a sleeve 23 which is rotatably 105 supported by the post 11, the sleeve 23 being held against vertical movement by means of a clamp 24 similar to the clamp 20. Upon the sleeve I mount the hub 25 of the gage-arm 26, said hub carrying a binding-screw 110 27. By means of this construction the gage-arm is not only rotatably mounted, but is

also vertically adjustable, the binding-screw 15 acting to hold the gage-arm in adjusted positions.

As will be seen in Fig. 2, the arm 10 is provided with a slot 28, in which the post 11 is slidably mounted, this being for the purpose of permitting said post to be drawn inwardly or outwardly relative to the center of the platform, whereby skirts of varying 10 diameters may be more readily placed in proper position for marking, a wing-nut 29 being employed to fasten the post in adjusted positions.

I claim as my invention:

- 15 1. In a skirt marking device, a platform, a movable gage adjacent thereto consisting of a marking plate, a pivotally mounted gage-arm adjacent said marking-plate, and a movable support for said marking plate and gage-arm, said marking plate being immovably secured to the movable support.
- 20 2. In a skirt-marking device, a platform, a relatively deep marking plate adjacent thereto, and a vertically movable pivotally mounted gage-arm adjacent the marking-plate having a relatively wide top surface.
- 25 3. In a skirt-marking device, a platform, a movable supporting arm adjacent thereto, a vertical post carried by said arm and adjustably connected thereto, and a vertically adjustable gage carried by said post and consisting of a marking-plate, and a gage-arm pivotally mounted on said post.
- 30 4. In a skirt-marking device, a platform, a movable supporting arm adjacent thereto, a square vertical post carried by said supporting arm, a bracket slidably supported thereby and having a square bore to fit said

post, a marking plate carried by said bracket, and a gage-arm pivotally mounted 40 on said post.

5. In a skirt-marking device, a platform, a movable supporting arm adjacent thereto, a vertical post carried by said supporting arm, a bracket slidably supported thereby 45 and having a bore to fit said post, a marking-plate carried by said bracket, a gage-arm having a hub provided with a bore to fit said post, said hub resting upon the said bracket, and retaining means carried by the 50 bracket engaging the hub of said gage-arm and arranged to permit said gage-arm to be rotated.

6. In a skirt-marking device, a platform, a movable supporting arm adjacent thereto, 55 a vertical post carried by said supporting arm, a bracket slidably supported thereby and having a bore to fit said post, a marking-plate carried by said bracket, a sleeve 60 also carried by said post having a bore to fit over said post, retaining means carried by said bracket and engaging said sleeve, and a vertically adjustable gage-arm rotatably supported by said sleeve.

7. In a skirt-marking device, a platform, 65 a movable supporting arm adjacent thereto, a vertical post adjustably connected to said arm, a vertically adjustable gage carried by said post, and a gage-arm pivotally mounted on said post.

Signed at New York city, N. Y., this 14th day of August, 1916.

EDWARD LEVIN.
